UNITED STATES PATENT OFFICE.

JOHN BOSSARD, OF DUBUQUE, IOWA.

ELECTROPLATING-HOOK.

SPECIFICATION forming part of Letters Patent No. 579,124, dated March 23, 1897.

Application filed April 25, 1896. Serial No. 589,132. (No model.)

To all whom it may concern:

Be it known that I, JOHN BOSSARD, a citizen of the United States, residing at Dubuque, in the county of Dubuque and State of Iowa, have invented certain new and useful Improvements in Electroplating-Hooks; and I do hereby declare the following to be a full, clear, and exact description of the invention, such as will enable others skilled in the art to

10 which it appertains to make and use the same.

My invention relates to electrodepositing devices in which the articles to be deposited upon travel around in or are drawn through the plating-bath by mechanical means and 15 receive the deposit similar to that described in Letters Patent granted to me on the 23d day of July, 1895, and numbered 542,986. It has special reference to the means of suspending the articles in the bath while they are being carried therethrough; and it essentially 20 consists in the novel suspension-hooks with other appliances, whereby the articles which are attached to the hooks are mechanically revolved or partially turned as they are drawn 25 through the bath to avoid what is known as "shading," and to make more even the deposit on all parts of the articles of whatever shape.

In explaining my device it will be necessary to refer to certain drawings, which form 30 a part hereof, and in which—

Figure 1 is a plan of a segment of the cathode strip and a clamp fastened upon it and a section of the body of the hook of one form. Fig. 2 is a segment of a cathode strip and deflecting-clamp in plan view, and also shows 35 pin upon the clamp and arm of the hook, shown partially in section and partially in side elevation. Fig. 3 shows sections of the body of the hooks of different forms. Fig. 4 is a front view of a broken portion of a circular carrier, a cathode-plate, rail, and post for supporting the cathode plate and a view 40 of the hook suspended from the carrier, showing mode of revolving same. Fig. 5 shows a side view of the body of hook of one form and section of wheel on shank of hook. Fig. 6 is a plan view of a wheel to be attached to the body of the hook. Fig. 7 is a modification of 45 Fig. 6. Fig. 8 shows a modification of the cathode strip and means for operating the wheel shown in Fig. 7. Fig. 9 shows a sec-

tional view of the bridge from which the articles are suspended with a side elevation of the hook and the endless chain for advancing the 55 articles through the bath with a sectional view of the cathode strip or bars. Fig. 10 shows a side elevation, with part broken away, of a longitudinal tank with which my device may be used, a sectional view of which is 60 shown in Fig. 9.

Like letters of reference denote corresponding parts in all of the drawings.

A represents the body of my improved hook, which is made of copper or other electrical 65 conducting material, and is somewhat enlarged at the center and made of various shapes for purposes hereinafter described. The upper end is formed into a head a, for the purpose of loosely swiveling it to the 70 hooked portion B, as shown in Figs. 4, 9, and 10. The lower portion b terminates in any convenient shape or size to allow readily the securing thereto of the hook C by linking, soldering, or other convenient methods, or the 75 articles may be wired directly to the lower end of said body. This hook, above described, when used with my Patent No. 542,986, is suspended from a bridge D, a section of which is shown in Fig. 9 and a side elevation in Fig. 80 10, and rests against a cathode strip d, from which strip it receives the cathode-current. There is also attached to this strip d one or more clamps E or F, as shown in Figs. 1 and 2, and there may also be, for certain purposes 85 hereinafter explained, pins e, (shown in Figs. 4 and 10,) secured to said cathode strip d.

In Fig. 10 there is shown a longitudinal tank similar to that shown in my Patent No. 542,986, in which the points of the hooks B 90 protrude through the links of the endless chain R and rest on the top of the rigid bridge D. The tank S is supplied with the usual anodes T, suspended from the sides of the tank. There is also secured along the 95 side of the tank the cathode strip d, to which the clamps E and G and the pins e are attached.

The various figures not heretofore explained will be described and their uses explained in giving the manner of operating my device. 100 The articles to be plated are attached to the hook B at the lower end C or directly to the lower end of the body, and in this instance the body of the hook may have the shape of

X or Y, (shown in section in Fig. 3.) These hooks so formed with the articles attached to them are suspended from the top of the carrier or bridge D, as shown in Figs. 4, 9, and 10, 5 with the bodies X or Y of the hooks B bearing against the cathode strip d. As the hook is drawn along the bridge D by the endless chain R, as shown in Figs. 9 and 10, or travels with the circular carrier F (shown in Fig. 4) 10 the bodies Y or X will pass along, bearing against the cathode strip d, up the incline of the clamp E, and on reaching the abrupt end of said clamp will drop suddenly against the body of the strip d and at the same time turn 15 the article to be deposited upon partially around in the bath, stirring the bath to make it more active and at the same time bringing a different surface of the article to the anode influence. Again, if it is desired to partially 20 turn or revolve the articles as they are drawn through the bath then there may be attached to the body A of the hook a wheel Z. (Shown in Fig. 6.)

A convenient mode of construction of the 25 body of the hook and of the wheel is shown in Fig. 5, wherein the body A is formed in a square and the center of the wheel is also square, but the center of the wheel is a trifle larger than the body A to allow said wheel Z 30 to readily slide up and down upon the body A for the purpose of adjusting itself upon the hook to the plane of the cathode strip d. As the hook is drawn along, by the endless chain R, the edge of the cathode strip d the spokes 35 z of the wheel will impinge against the pins e on the strip d, and in this manner partially rotate the articles in the bath, or if the cathode strip has a clamp secured thereto, as shown in Fig. 2, the spokes z will impinge 40 against the pin f upon the clamp F, and also rotate the articles in the bath. It will be seen by this manner of turning the articles as they are carried through the bath that their entire 45 surface will be exposed to the influence of the anode and will evenly receive the deposit, and at the same time the bath will be agitated and kept active.

When it is desired to have the article to be 50 deposited upon constantly turned in the solution, the edge of the cathode strip d is formed into notches g, as shown in Fig. 8, and there is then attached to the body A of the hook the toothed wheel H. (Shown in Fig. 7.) Then as the articles are drawn along the teeth 55 upon the wheel H will engage with the notches g or teeth upon the strip d and constantly turn the articles, and it will be seen by this mode of suspending the articles in the bath the deposit will be done evenly upon all of the 60 surfaces and the bath will be constantly stirred and active.

It is manifest that various other forms may be given to the body A of the hook, adapted 65 to the shape of the articles to be deposited upon, the thought being to so sustain the articles of whatever shape as they are drawn through the bath that all their parts will be

equally exposed to the anode influence and evenly deposited upon and the bath at the same time kept ever active by the constant 70 stirring of the same caused by these various movements of the articles as they are advanced through the bath.

Having now described my invention, what I claim, and desire to secure by Letters Patent, is—

1. A hook of the character described, consisting of a hooked upper portion for engaging with a carrier, a body swiveled to said hook, a lower portion from which the articles 80 are suspended in the bath, means for causing the articles to be revolved while suspended from said hook in the bath and a carrier from which the hooks are suspended for advancing the articles along in the bath, as and for 85 the purposes shown.

2. A hook for sustaining the articles in a depositing-bath, consisting of a hooked upper portion, for engagement with a carrier, a body swiveled to said upper portion, a lower 90 portion from which the articles to be deposited upon are suspended in the bath, means for intermittently rotating the articles as they are drawn through the bath and a carrier from which the hooks are suspended, for advancing 95 the articles in the bath, as and for the purposes shown.

3. A hook for sustaining the articles in the plating-bath, consisting of the hook B, body A, swiveled to the hook B, wheel Z, adjustably attached to said body A, means for attaching the articles to be deposited upon to the body and strip d, provided with projections e, as and for the purposes shown.

4. The combination in an electrodepositing 105 device, of a carrier for drawing the articles through the bath, and a strip beneath said carrier, and a hook for sustaining the articles to be deposited upon in the bath, consisting of a hooked upper portion to engage with the carrier, a body swiveled to said upper portion and having projections thereon, a lower portion from which the articles are suspended in the bath and projections upon said strip 110 below the carrier, for engaging with the projections on said body, whereby the articles are rotated while being carried through the bath, for the purposes shown.

5. In combination with an electrodepositing 115 device, having a carrier for drawing the articles through the bath and a strip beneath said carrier, a hook for sustaining the articles to be deposited upon in the bath, consisting of a hooked upper portion to engage with the carrier an enlarged body swiveled 120 to the upper portion, a lower portion adapted to engage with the articles in the bath and means secured to the strip below the carrier, for engaging with the body of the hook, whereby the articles are intermittently rotated 125 while drawn through the bath, and the bath is stirred.

6. The combination in an electrodepositing 130 device, of a carrier for drawing the articles

through the bath, a rigid strip beneath said carrier, provided with projections thereon, with a hook for sustaining the articles to be deposited upon in the bath, consisting of the

5 hooked upper portion to engage with the carrier, a body swiveled to said hook and having projections thereon vertically adjustable and adapted to engage with the projections on said strip and means for attaching the articles to said body, as and for the purposes shown.

7. The combination in an electrodepositing device of a carrier for drawing the articles through the bath, a strip beneath said carrier, having projections upon its outer edge and a hook for sustaining the articles to be deposited upon in the bath, consisting of a hooked upper portion to engage with the carrier, a body swiveled to the hooked upper portion and having projections at or near the outer 15 edge of said strip and a lower portion for at-

tachment to the articles in the bath, whereby the articles are rotated while being drawn through the bath, substantially as and for the purposes shown.

25

8. The combination in an electroplating device of a carrier for drawing the articles through the bath, a cathode strip *d*, below said carrier, one or more clamps *G*, attached to the outer edge of the cathode strip and 30 provided with projections *f*, and a hook for suspending the articles in the bath from said carrier, having a hooked upper portion *B*, body *A*, swiveled to the hooked upper portion and a lower portion *b*, all combined substantially as and for the purposes shown.

In testimony whereof I affix my signature in the presence of two witnesses.

JOHN BOSSARD.
